US0D1111662S

(12) **United States Design Patent** (10) **Patent No.:** **US D1,111,662 S**
(45) **Date of Patent:** **** Feb. 10, 2026**

(54) **ICE SHAVER ATTACHMENT**

(71) Applicant: **Dongguan Hongying Electric Technology Co., LTD**, Dongguan (CN)

(72) Inventor: **Jiaying Lin**, Dongguan (CN)

(73) Assignee: **Dongguan Hongying Electric Technology Co., LTD**, Dongguan (CN)

(**) Term: **15 Years**

(21) Appl. No.: **29/907,815**

(22) Filed: **Jan. 9, 2024**

(30) **Foreign Application Priority Data**

Dec. 9, 2023 (CN) 202330811871.1

(51) **LOC (15) Cl.** **31-00**

(57) **CLAIM**

The ornamental design for an ice shaver attachment, as shown and described.

DESCRIPTION

FIG. 1 is a perspective view of my new design, showing an ice shaver attachment;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The line shading in FIGS. 1-8 represents contour and not surface ornamentation.

The broken lines shown in the figures illustrate environmental or other features that form no part of the claimed design.

1 Claim, 8 Drawing Sheets
